CLAIM

The ornamental design for a dump bin, as shown and described.

DESCRIPTION

FIG. 1 is a front perspective view looking from the top and front of a dump bin showing my new design, the opposite perspective view being a mirror image; FIG. 2 is a front elevational view thereof; and, FIG. 3 is a top plan view thereof.
The undisclosed bottom is flat and unornamented.

FIG. 3

FIG. 2

FIG. 1
